UNITED STATES PATENT OFFICE.

WELFORD CLARENCE DIAL, OF PUEBLO, COLORADO.

ENGINE EXHAUST.

Application filed April 29, 1925. Serial No. 26,768.

To all whom it may concern:

Be it known that I, WELFORD CLARENCE DIAL, a citizen of the United States, residing at Pueblo, in the county of Pueblo, State of Colorado, have invented certain new and useful Improvements in Engine Exhausts, of which the following is a specification.

This invention relates in general to engine exhausts and is particularly designed **10** to be used with the exhaust systems of internal combustion engines of the type used on automobiles.

The object of the invention is the provision of an engine exhaust which embodies **15** a cut-out that may be readily opened to permit the gases to pass directly from the engine to the atmosphere, but in which there is normally provided a complete and unbroken exhaust line so that the gases pass through **20** the muffler ordinarily provided.

One of the principal objects of the invention resides in the provision of a simple, durable and practical means of the character specified which is easily operated **25** by the driver of the automobile, which is not liable to get out of order, and which is comparatively inexpensive to manufacture and apply.

30 A further object is the provision of a device of this character which eliminates butterfly valves or other types of valves liable to become stuck by deposits of carbon or other deposits.

Other objects and advantages reside in **35** certain novel features of the construction, arrangement and combination of parts which will be hereinafter more fully described and particularly pointed out in the appended claims, reference being had to the accompanying drawings forming a part of this specification, and in which:

Figure 1 is a fragmentary view partly **45** in section and partly in elevation showing one embodiment of the invention,

Figure 2 is a view in section on the line **50** 2-2 of Figure 3, and

Figure 3 is a view in section on the line **55** 3-3 of Figure 2.

Referring to the drawings the numeral 1 **60** designates the internal combustion engine of an automobile, and the numeral 2 designates the floor boards of the body thereof. The engine 1 has an exhaust manifold 3 from which an exhaust conduit 4 leads. The

exhaust conduit 4 includes a stationary section 5 suitably supported on the body of the automobile, and a movable section 6 having a flexible pipe 7 connecting the same with the exhaust manifold. The stationary section 5 is connected with the muffler (not **65** shown) which is ordinarily provided on an automobile. The sections 5 and 6 are rigid and may be ordinary metallic piping. The adjacent ends of the sections 5 and 6 are beveled, as indicated at 5^a and 6^a and are **70** adapted to be telescoped or interfitted as clearly shown in Figure 2. When so telescoped or interfitted there is provided a continuous unbroken exhaust line which leads from the engine through the muffler in the **75** ordinary way. When the section 6 is withdrawn from the section 5 and shifted laterally with respect thereto, as shown in dotted lines in Fig. 1, the engine exhausts directly to the atmosphere to provide a cut- **80** out.

As shown in Figures 2 and 3 the pipe 5 may be suitably secured to a bracket, designated generally at 8, and secured to a supporting plate 9 fastened to the floor boards 2. The **85** pipe 6 operates in a guide 10 depending from the plate 9.

Means is provided for moving the movable section 6 so as to withdraw the same **90** from the section 5 and then shift the same laterally with respect to the section 5 and to the position shown in dotted lines in Figure 1, and such means preferably includes a shaft 12 rotatably supported in suitable bearings provided therefor in a bracket 13 **95** carried by the bracket 8. A U-shaped crank 14 is fixed to the shaft 12 and has a pair of crank arms 15 which straddle the movable section 6 and which are pivotally connected thereto, as by means of a pivot pin 16.

Foot control means is provided for turning the shaft 12 and comprises a pinion 17 fixed to the shaft 12 and meshing with a rack 18, which operates through guides 19 **100** and 20 provided in the brackets 13 and 8, respectively, and which extends up above the floor boards 2. On the upper end of the rack 18 a foot piece 21 is provided.

The rack 18 is normally held in elevated **105** position by means of a retractile coil spring 22 having one end connected, as at 23, to the plate 9 and having its other end con-

nected, as at 24, to the rack 18. By elevating the rack 18 the spring 22 biases the shaft 12 to such a position as to cause the sections 5 and 6 to be interfitted, as shown in Figure 2.

For the purpose of releasably securing the rack 18 in depressed position, the rack is provided with a notch 25 which provides a shoulder 26 engageable with the plate 9 to hold the rack depressed. The guides in which the rack operates are designed to permit such rocking movement of the rack as may be necessary to engage the shoulder 26 with the plate 9.

With this arrangement the sections 5 and 6 are normally interfitted as shown in Figure 2 and consequently there is provided a complete unbroken exhaust line so that the exhaust passes through the muffler in the usual manner. The parts are held in such position by the action of the spring 22 as well as by the frictional engagement of the parts 5 and 6 and their inertia.

When it is desired to have the engine exhaust directly to the atmosphere or in other words to cut out the muffler, the operator of the machine merely depresses the rack 18 which rotates the pinion 17 and the shaft 12. The crank arms 15 move with the shaft 12. As shown in Figure 2, when the sections 5 and 6 are interfitted, the crank arms 15 are vertically disposed. Consequently, when the shaft 12 first begins to move, the section 6 is moved approximately axially and away from the section 5. As the crank arms 15 continue to swing the vertical component of their angular motion increases and the horizontal component of their angular motion decreases so that toward the end of their movement they shift the movable section downwardly or laterally with respect to the stationary section. When the rack 18 is released it is moved upwardly by the action of the spring 22 and the movement of the crank arms 15 and section 6 is reversed to cause the sections 5 and 6 to again be interfitted.

I claim:

1. In an engine exhaust, an exhaust conduit including sections having interfitted ends designed when interfitted to provide a complete exhaust conduit and when separated to provide a broken exhaust conduit providing a cut-out, and means for causing said sections to be interfitted or to be separated.

2. In an engine exhaust, an exhaust conduit including a stationary section and a movable section, the movable section having an end designed to be fitted into one end of the stationary section.

3. In an engine exhaust, an exhaust conduit including a stationary section and a movable section, the movable section having an end designed to be fitted into one end of

the stationary section, said interfitting ends being bevelled.

4. In an engine exhaust, an exhaust conduit including a stationary section and a movable section, the movable section having an end designed to be fitted into one end of the stationary section, means for operating the movable section including a bracket, a shaft rotatably mounted on the bracket, a crank arm fixed to the shaft and connected with the movable section, and means for turning the shaft.

5. In an engine exhaust, an exhaust conduit including a stationary section and a movable section, the movable section having an end designed to be fitted into one end of the stationary section, means for operating the movable section including a bracket, a shaft rotatably mounted on the bracket, a crank arm fixed to the shaft and connected with the movable section, foot controlled means for turning the shaft to separate the sections, and spring means for biasing the shaft to such position as to cause the sections to be interfitted. 90

6. In an engine exhaust, an exhaust conduit including a stationary section and a movable section, the movable section having an end designed to be fitted into one end of the stationary section, means for operating the movable section including a bracket, a shaft rotatably mounted on the bracket, a crank arm fixed to the shaft and connected with the movable section, foot controlled means for turning the shaft to 95 separate the sections, spring means for biasing the shaft to such position as to cause the sections to be interfitted, and means for locking the foot operated means in such position as to releasably hold the sections of 100 the conduit separated.

7. In an engine exhaust, an exhaust conduit including a stationary section and a movable section, the movable section having an end designed to be fitted into one 110 end of the stationary section, means for operating the movable section including a bracket, a shaft rotatably mounted on the bracket, a crank arm fixed to the shaft and connected with the movable section, foot controlled means for turning the shaft to 115 separate the sections and comprising a pinion fixed to the shaft, a rack meshed with the pinion and a foot piece connected with the rack, and spring means for biasing the shaft to such position as to cause the sections to be interfitted.

8. In an engine exhaust, an exhaust conduit including a stationary section adapted to be connected with a muffler, and a movable section having a flexible portion adapted to be connected with the engine, the movable section having an end designed to telescope in an end of the stationary section, the movable section being adapted to be 125 130

shifted out of the stationary section and then laterally thereof, and means for shifting the movable section.

9. In an engine exhaust, an exhaust conduit including a stationary section adapted to be connected with a muffler, a movable section having a flexible portion adapted to be connected with the engine, the movable section having an end designed to telescope in an end of the stationary section, the movable section being adapted to be shifted out of the stationary section and then laterally thereof, and means for shifting the movable section and including a
10. In an engine exhaust, an exhaust conduit including a stationary section adapted to be connected with a muffler, a movable section having a flexible portion adapted to be connected with the engine, the movable section having an end designed to telescope in an end of the stationary section, the movable section being adapted to be shifted out of the stationary section and then laterally thereof, means for shifting the movable section and including a

20
25
30

shaft having a crank arm connected with the movable section, and a guide co-acting with the movable section to constrain it to proper movement.

W. CLARENCE DIAL.
